UNITED STATES PATENT OFFICE.

WILLIAM T. GABLE, OF BALTIMORE, MARYLAND, ASSIGNOR TO BETHLEHEM STEEL COMPANY, OF BETHLEHEM, PENNSYLVANIA.

THREADING MACHINE.

Application filed March 11, 1924. Serial No. 698,403.

To all whom it may concern:

Be it known that I, WILLIAM T. GABLE, a citizen of the United States, and residing at Baltimore city, State of Maryland, have invented certain new and useful Improvements in Threading Machines, of which the following is a specification.

My invention relates to threading machines of the general type disclosed in the 10 patent to Adams No. 357,300, dated Feb. 8, 1887, and it has for an object to render machines of this character safer to operate and to increase the productive capacity thereof.

More specifically my invention has for an 15 object to provide a threading machine of the character indicated in which the threading die is automatically opened after threading to a predetermined extent.

Referring to the patent to Adams aforesaid, it will be noted that the dies are opened and closed by means of a collar which is movable longitudinally of the arbor. Opening movement is accomplished by means of a pin which comes into engagement with a 20 lateral cam on the collar when the latch mechanism of the pin is released. Such latch mechanism is ordinarily released by a wedge block carried on a rod movable with the chuck carriage. The pin remains in engagement with the cam groove in the collar until it is again latched, movement thereof for this purpose being effected by peripheral cam portions on the collar. The dies are 25 closed by backward movement of the chuck carriage, which operates through a rod and a collar to swing a lever, which, in turn, pushes the collar in a direction opposite to that in which it has been moved in order to open the die. It has happened in some 30 cases that the die would be closed without the pin being disengaged and with the collar resting against the lever. In such a case, the pin would act on the cam to move the 35 collar and open the die and the movement of the collar would pull the chuck carriage toward the die head. If a workman should have his hands between the chuck and the die head he might be injured due to this 40 movement particularly if he happens to be working with close clearance between the chuck and the die head as would likely be the case if he was attempting a high rate of production or was threading short stock. My invention, therefore, has for an object 45 to provide means for automatically moving

the actuating wedge out of the way just as soon as the pin starts to move toward the cam collar with the result that the latch mechanism is free to lock the pin in inactive or disengaged position as soon as it is 60 moved to the latter position by a peripheral cam portion. Regardless of the setting of the closing lever or the opening wedge or the close clearance between the chuck and the die head, it is, therefore, impossible to 65 bring about the dangerous reactive operation and consequent movement of the chuck toward the die head in the manner just referred to.

A further object of my invention is to 70 provide a threading machine for threading nipples or pipes incorporating a reamer mounted on a push rod extending through the arbor, the push rod being connected to an automatic tripping device, whereby a 75 predetermined and exact length of thread may be provided on pipes or nipples.

Apparatus made in accordance with my invention is illustrated on the accompanying drawings, forming a part of this application, in which:

Figure 1 is a longitudinal sectional view of a threading machine having my improvements applied thereto;

Figure 2 is a sectional detail view taken along the line II—II of Figure 1;

Figure 3 is a detail view of a reamer and associated parts;

Figure 4 is a plan view of a machine such as illustrated in Figure 1;

Figure 5 is a sectional view taken along the line V—V of Figure 4 and showing a portion of the reamer push-rod actuated mechanism;

Figures 6, 7 and 8 are detail views showing parts of the reamer push rod operating mechanism to bring about opening of the dies;

Figure 9 is a detail view showing latch mechanism for holding the cam pin retracted;

Figure 10 is a sectional view taken along the line X—X of Figure 9;

Figure 11 is a sectional view taken along the line XI—XI of Figure 4;

Figures 12, 13, 14 and 15 are detail views showing releasing wedge elements attached to a rod moved by the chuck carriage; Figure 14 being a section along the line XIV—XIV of Figure 9, and Figure 15 be-

ing a section along the line XV—XV of Figure 14; and

Figure 16 is a detail view of a wedge device for attachment to a reamer actuated by a rod as illustrated in Figure 4.

Referring now to the drawings more in detail for a better understanding of my invention, I show a threading machine having a pedestal support 10 carrying a bed 11.

10 An arm 12 preferably extends from the pedestal 10 to provide a support 13 for a shaft or rod element 14 which is connected to the bed.

A stepped pulley 15, or other suitable speed change device, is mounted on the shaft 14 and I show such stepped pulley connected to a spur pinion 16 meshing with a gear 17, which is keyed to a hollow arbor 18.

The hollow arbor is journaled in bearings 19 carried by the bed 11 and it supports at its end opposite to the gear 17 an opening and closing die, at 20, of the general character disclosed in the patent aforesaid.

25 A chuck carriage 22 mounted in suitable guideways 23 in the bed 11 is movable toward and away from the die 20 by any suitable means, as by a pinion 24 meshing with a rack 25 on the carriage, the pinion 24 being keyed to a shaft 26 which is operated by a suitable handwheel 27. A chuck or work holder comprising jaws 28 and 29 is movable transversely of the carriage on a suitable guideway 30 in order to grip or release any suitable work to be threaded.

With the apparatus so far described, work is placed between the chuck jaws 28 and 29 and the carriage 25 is moved toward the die until the work initially engages with the 40 cutters, whereupon threads are cut on the work and the work is fed in automatically, the die acting as a nut on the threads being cut.

The die 20 is opened and closed by means 45 of a collar 32 which has peripheral and lateral cam portions 33 and 34. Opening of the dies is accomplished by engagement of the pin 35 with one of the lateral cam portions 34 resulting in movement of the collar 32 away from the die and opening of the latter. The die may be closed by an abutment 36 carried by a lever 37 having an abutment end 38 in the path of the collar 39 carried by a rod 40 connected to the 55 chuck carriage.

It will be obvious to those skilled in the art that any suitable die device may be used so long as it is of the opening and closing type. I prefer to use a two-part die head actuated by mechanism of the general character indicated in the patent aforesaid. As the die per se does not constitute a part of my invention, it is deemed to be unnecessary to refer to it in greater detail.

60 Assuming that the die is closed, opening

thereof is accomplished by upward movement of the pin 35 in the guideway recess 42 formed in a suitable bracket or frame 42' secured to the machine. The pin 35 is normally biased in an upward direction by a spring 43 arranged between a shoulder 44 on the pin and a shoulder 44' of the recess. The pin 35 is withheld in inactive or disengaged position by means of a slidable latch rod 45 having a latch tongue portion 46 for engagement behind a shoulder 47 on the pin 35. The latch rod is mounted in suitable guide bearings 48 and 49 in the frame 42', a space being provided between the bearings 48 and 49 so that a spring 50 70 may surround the rod 45 and abut at one end against the end of the bearing 49, the other end of the spring abutting against a collar 51 secured to the rod 45, whereby the rod 45 and the latch portion 46 are biased 75 in a direction to engage the latch portion 46 behind the shoulder 47 to hold the rod 45 in retracted position.

As soon as the latch rod 45 is moved to disengage the latch portion 46 from behind the shoulder 47, the pin 35 moves up to engage a lateral cam portion in the manner just referred to, this movement of the latch rod 45 being brought about by a wedge element 52 carried by a suitable moving part 95 of the machine, the wedge element 52 engaging with an abutment bearing surface 53 on the rod 45.

The wedge element may be carried either by the rod 40 already referred to or by a 100 rod 54 actuated from the reamer. The reamer actuating mechanism will now be described.

Referring to Figures 1 and 3, it will be seen that I show a reamer 55 having a universal or wobbling connection 56 with respect to a push rod 57, these parts being arranged within the die and within the hollow arbor 18 as shown in Figure 1. The outer end of the push rod 57 is connected to a collar 58 which actuates the yoke 59 of a lever 60 fulcrumed at 61, the other end of the lever having a slip-joint connection 62 with respect to a coupling member 63 connected to the rod 54. As illustrated in Figures 6 and 7, the coupling member 63 passes through a bracket bearing 64, the latter constituting a support for a spring 65 bearing against a collar 66 on the connection 63. The compression of the spring 65 tends to move the push rod and reamer toward the front of the die. The position of the reamer 55 with respect to the die 20 may be adjusted by setting the collar 58 on the shaft 57, a set screw 58' being provided for 110 this purpose. See Figures 4 and 6.

The wedge element 52 has a wedging surface 68 for engagement with the abutment portion 53 to release the latch rod 45 in the manner aforesaid. The wedge elements 120

130

for attachment to the reamer actuated rod 54 or to the chuck carriage rod 40 are similar except that one is the reverse of the other. In Figures 12, 13, 14 and 15, I show a wedge element 52 of a design suitable for use on a chuck carriage rod. In Figure 16, I show a similar wedge element 52' for use on a reamer actuated rod 54, the principal difference between the wedge elements being that they extend in opposite directions and, therefore, the design must be reversed.

Each of the wedge elements 52 and 52' has a pivotal connection 69 with respect to 15 a carrier block 70 having a set screw or equivalent means 71 for adjusting the carrier block to any suitable position along the rods 54 or 40. The wedge members 52 or 52' are biased about the pivotal connection 20 69 by means of a spring 72 so that the inclined or wedging surface 68 is normally located in a path to engage the latch rod abutment 53. Biasing movement of the latch member is limited by any suitable 25 stop or abutment 73 on the block 70.

I provide for disengagement of the latch member 52 or 52' with respect to the abutment 53 of the latch rod just as soon as the pin 35 starts to move toward the cam collar 32, thereby permitting movement of the latch rod 45 toward the pin 35 and engagement of the latch tongue 46 behind the shoulder 47 just as soon as the pin 35 is moved to inactive or retracted position by 35 a radial or peripheral cam portion 33. Accordingly, I show the lower end of the pin 35 pivotally connected to a lever 74 fulcrumed at an intermediate point 75, the other end of the lever 76 being adapted to 40 overhang a lip 77 on a wedge element 52 or 52'. When the wedge element 52 or 52' occupies a position such that the latch rod 45 is released from the pin 35 the end portion 76 will be immediately above the lip 45 77; and, just as soon as upward movement of the pin 35 commences the lever 74 starts to move in such a direction that the end 76 moves the pivoted wedge member 52 or 52' about its pivot 69 and disengages the inclined or wedged surface 68 from the latch rod abutment 53. This disengaging movement is indicated by dotted lines in Figure 50 10. Just as soon as the wedge surface 68 is disengaged, the latch rod 54 is free to move over toward the pin 35, thereby preventing the wedge surface from coming back into engagement with the abutment 53 when the pin is moved out by a peripheral or radial cam portion 33. As the pin 35 moves up 55 to engage a lateral cam portion 34 to open the die 20, the latch rod 45 is automatically released from the wedging device which brought about the unlatching and the pin 35 is, therefore, automatically latched in retracted position as soon as it is pushed to

that position by the next succeeding radial cam.

Upon reference to Figure 3, it will be noted that the reamer 55 is provided with interior reamer edges 55^a to remove interior 70 burrs, etc., with chamfering edges 55^b to chamfer off the threaded pipe or nipple end to prevent injury to the threads in handling, and with burnishing and abutment edges 55^c which burnish the pipe or nipple end 75 and serve as abutment surfaces so that the feeding-in motion of the work may move the push rod 57 to operate the latching devices in the manner aforesaid.

My improved threading machine operates 80 as follows: If nipples or pipes are threaded, the work is placed in the chuck and fed into the die. Thereafter the work is fed by the thread cutting action of the die. At the same time, the reamer removes interior 85 burrs, chamfers the end, and burnishes the end; and the work acting on the abutment edges 55^c of the reamer causes movement of the push rod 57 toward the left, in Figure 1, which results in movement of the 90 lateral rod 54 toward the right, in Figure 4, to bring the wedge 68 of the wedge element 52' into engagement with the abutment 53 of the latch rod 45, whereupon the latter is moved to disengage its latch tongue 95 from behind the shoulder 47 on the pin 35, permitting the spring 43 to move the cam pin 35 up into engagement with a lateral cam 34 to effect opening of the die. Concurrently with the upward movement of the 100 pin 35, the lever 74 moves the wedge element 52' out of engagement with the abutment 53 so that the latch rod 45 is free to engage behind the shoulder 47 as soon as the pin 35 is depressed by a radial or peripheral cam 33. 105

The length of thread on a nipple or pipe may be regulated by adjusting the collar 58 on the push rod 57 or by adjustment of the block 70 on the rod 54.

If the machine is used to thread bolts or rods, the reamer is removed, and a block 70 having a wedge element 52 (see Figures 12, 13, 14 and 15) is placed on the chuck carriage rod 40. The machine now operates similarly to that disclosed in the patent aforesaid except that, with my machine, the wedge element 52 is released by the upward movement of the pin 35 resulting in immediate locking of the latter pin in disengaged or inactive position, thereby avoiding the possibility of having the carriage pulled toward the die head by the pin engaging a lateral cam.

From the foregoing, it will be apparent that I have provided an unlatching mechanism for a cam pin which is rendered ineffective as soon as the pin starts toward cam-engaging position, thereby making it possible to latch the cam pin in retracted position as soon as the next peripheral cam 130

portion for this purpose comes into engagement therewith thereby making it impossible, with a machine of this character, by improper or hasty operation to bring about 5 accidental movement of the chuck carriage toward the die. It will also be apparent that, with my improved type of threading machine, threads may be cut on pipes, nipples or rods to predetermined lengths and 10 with great rapidity.

Having thus described the invention what I claim as new and desire to secure by Letters Patent is:

1. In a threading machine, the combination of an opening and closing die, means for opening the die including a movable member, latch mechanism for holding the movable member in retracted or disengaged position, an element moved by the machine 15 for disengaging the latch mechanism, and means operated by said member in moving to die-opening position to disengage said element from the latch mechanism.
2. In a threading machine, the combination of an opening and closing die, means to open the die, means to render the last-named means effective including a movable element, means for biasing the movable element in one direction, a latch for holding 20 the movable element in inactive position, an abutment on the latch, means carried by a movable part of the machine and cooperating with the abutment to withdraw the latch so that said movable element is free 25 to move in its biased direction, and means actuated by the movable element to move the last-named means away from the abutment, whereby the latch may move toward latching position and engage the movable element 30 as soon as the latter is moved in the other direction to a predetermined extent.
3. In a threading machine, the combination of an opening and closing die, means to open the die, means to render the last-named means effective including a pin, a spring for moving the pin in an engaging direction, a shoulder carried by the pin, a latch for engagement with the shoulder to hold the pin disengaged, an abutment 35 on the latch, a wedge carried by a movable part of the machine for withdrawing the latch in order that the spring may move the pin in an engaging direction, and means actuated by the pin in moving in 40 an engaging direction to move the wedge away from the latch abutment, whereby the latch may move toward latching position and engage behind the shoulder of the pin as soon as the latter is moved in a disengaging direction to a predetermined extent.
4. In a threading machine, the combination of an opening and closing die, a reciprocal collar for opening the die, lateral and peripheral cams carried by the 45 collar, a reciprocal pin for engagement 50

with the cams, a spring for moving the pin into engagement with the cams, a shoulder carried by the pin, a latch rod for cooperation with the shoulder to hold the pin disengaged from the cams, an abutment carried 55 by the latch rod, means for biasing the latch rod toward the pin, a member movable incident to the operation of the machine, a wedge pivoted to said member and adapted to engage the latch rod abutment to withdraw the latch rod from engagement with the pin shoulder, and means actuated by the pin for disengaging the wedge from the latch rod abutment, whereby the latch rod may move in a latching direction and engage the abutment of the pin as soon as the latter is moved by a peripheral cam to an extent sufficient for the pin shoulder to pass beyond the latch rod in one direction.

5. In a threading machine, the combination of an opening and closing die, means to open the die including a reciprocable cam collar having lateral and peripheral cam portions, a reciprocable pin for engagement with the lateral cam portions to secure movement of the collar in one direction and engaged by the peripheral cam portions to be moved to inactive position, a spring for moving the pin into cam-engaging position, a shoulder carried by the pin, a latch rod for engagement with the shoulder to hold the pin in inactive position, a spring for moving the latch rod into engagement with the pin shoulder, an abutment carried by the latch rod, a shaft which moves longitudinally in 60 incident to operation of the machine, a wedge element pivotally mounted with respect to said shaft and moved by the latter into engagement with the latch rod abutment to disengage the latch rod from the pin, and means actuated by movement of the pin in a cam-engaging direction to move the wedge about its pivot away from the latch rod abutment, whereby the latch rod is moved immediately by its spring toward the pin and engages behind the shoulder of the latter as soon as the pin is moved in a disengaging direction to a sufficient extent by one of the peripheral cams.

6. In a threading machine, the combination of an opening and closing die, means to open the die including a reciprocable collar, lateral and peripheral cam portions on the collar, a slidably pin for engagement with a lateral cam portion to secure movement of the collar in a direction to open the die and for engagement with a peripheral cam portion in order that the pin may be moved to inactive position, a spring cooperating with the pin to move it in a cam-engaging direction, a shoulder carried by the pin, a latch member for engagement with the shoulder to hold the pin in disengaging position, a spring for holding the latch member in engagement with the shoulder,

an abutment carried by the latch member, a member which moves longitudinally of the machine incident to the operation of the latter, a wedge pivoted to said member, 5 means for biasing the wedge to such a position as to engage with the latch member abutment, a lever fulcrumed at an intermediate point and having one end connected to the pin and the other end adapted to 10 engage with the wedge, whereby, upon movement of the pin in a cam-engaging direction, the lever is operated to withdraw the wedge from the latch member abutment whereupon the latch member moves under the influence 15 of its spring toward the pin and engages behind the abutment of the latter as soon as the pin is moved to a sufficient extent by a peripheral cam.

7. In a threading machine, the combination 20 of an opening and closing die, means to open the die including a reciprocable collar having peripheral and lateral cam portions, a pin movable toward and away from the collar, a spring for moving the pin toward 25 the collar, said pin engaging a lateral cam portion to move the collar in a direction to open the die and being engaged by peripheral cam portion in order that it may be moved away from the collar, a

shoulder on the pin, a latch member for 30 engagement behind the shoulder to hold the pin out of engagement with the cam portions, a spring cooperating with the latch member to move the latter in a shoulder-engaging direction, an abutment carried by 35 the latch member, a member movable longitudinally of the machine incident to the operation of the latter, a wedge pivotally mounted with respect to the latter member

40 and adapted to engage with the abutment of the latch member to withdraw the latter from the shoulder, means for biasing the wedge to a position such that it may engage the latch member abutment, a lateral 45 shoulder carried by the wedge, a lever fulcrumed at an intermediate point and having one end connected to the rod and having its other end adapted to be arranged over the shoulder of the wedge when the latter

50 is moved into position to engage with the latch member abutment, whereby, when the pin moves toward the collar the lever engages the wedge shoulder to withdraw the wedge from the latch member abutment permitting 55 the latch member to move toward the pin so that it may engage behind the shoulder of the latter when the pin is moved away from the collar by a peripheral cam.

8. In a pipe or nipple threading machine, 60 the combination of a hollow arbor, an opening and closing die carried by the arbor, a work holder, a reamer in the die and having abutment surfaces, a push rod connected to the reamer and adapted to be moved by the work abutting the abutment surfaces of the latter, a collar movable on the arbor to open the die, lateral and peripheral cam portions on the collar, a pin movable into engagement with a lateral cam

surfaces of the latter, a collar movable on the arbor to open the die, lateral and peripheral cam portions on the collar, a pin movable into engagement with a lateral cam portion to open the die and being movable to an inactive position by a peripheral cam portion, a spring for moving the pin toward the collar, latch mechanism for holding the pin in disengaged position, means operated by the push rod for disengaging the latch mechanism from the pin whereupon the latter moves into engagement with a lateral cam portion to open the die, means operated by the pin during its cam-engaging movement to disengage said push-rod operated mechanism from the latch mechanism to permit the latter to lock the pin in disengaged position when such pin is moved away from the collar to a sufficient extent by a peripheral cam portion, and means rendered effective by backward movement of the work holder to close the die.

9. In a pipe or nipple threading machine, the combination of a hollow arbor, an opening and closing die carried by the arbor, a work holder, a reamer in the die and having abutment surfaces, a push rod connected to the reamer and adapted to be moved by the work abutting the abutment surfaces of the latter, a collar movable on the arbor

to open the die, lateral and peripheral cam portions on the collar, a pin movable into engagement with a lateral cam portion to open the die and being movable to an inactive position by a peripheral cam portion,

a spring for moving the pin toward the collar, a shoulder on the pin, a longitudinally-movable latching member for engagement behind the shoulder to hold the pin retracted, a spring for moving the member to engage behind the shoulder, an abutment on said member, a rod movable by said push rod, a wedge member pivotally mounted with respect to the last-named rod and adapted to engage said abutment, means for biasing

the wedge member to the abutment-engaging path, and means operated by the pin in moving toward the cam collar for disengaging said wedge element from the abutment, whereby said member immediately moves toward the pin and engages behind the shoulder of the latter as soon as such pin is moved to inactive position by a peripheral cam portion.

10. In a pipe or nipple threading machine, the combination of a hollow arbor, an opening and closing die carried by the arbor, a reamer in the die and having abutment surfaces, a push rod in the arbor and connected to the reamer and adapted to be moved by the work abutting the abutment surfaces of the latter, a collar movable on the arbor to open the die, lateral and peripheral cam portions on the collar, a pin movable into engagement with a lateral cam

surfaces of the latter, a collar movable on the arbor to open the die, lateral and peripheral cam portions on the collar, a pin movable into engagement with a lateral cam portion to open the die and being movable to an inactive position by a peripheral cam portion, a spring for moving the pin toward the collar, latch mechanism for holding the pin in disengaged position, means operated by the push rod for disengaging the latch mechanism from the pin whereupon the latter moves into engagement with a lateral cam portion to open the die, means operated by the pin during its cam-engaging movement to disengage said push-rod operated mechanism from the latch mechanism to permit the latter to lock the pin in disengaged position when such pin is moved away from the collar to a sufficient extent by a peripheral cam portion, and means rendered effective by backward movement of the work holder to close the die.

portion to open the die and being movable to an inactive position by a peripheral cam portion, a spring for moving the pin toward the collar, a shoulder on the pin, a longitudinally movable latching member for engagement behind the shoulder to hold the pin retracted, a spring for moving the member to engage behind the shoulder, an abutment on said member, a lever pivotally connected at one end to the push rod and fulcrumed at an intermediate point, a lateral rod pivotally connected to the other end of the lever, an adjustably mounted block on the lateral rod, a wedge member pivoted to the block and adapted to engage said abutment for withdrawing the latching member from the shoulder, means for biasing the wedge member to the abutment-engaging path, and means operated by the pin in moving toward the cam collar for disengaging said wedge element from the abutment, whereby said member immediately moves toward the pin and engages behind the shoulder of the latter as soon as such pin is moved in inactive position by a peripheral cam portion.

11. In a pipe or nipple threading machine, the combination of a hollow arbor, an opening and closing die carried by the arbor, a reamer in the die and having abutment surfaces, a push rod in the arbor and connected to the reamer and adapted to be moved by the work abutting the abutment surfaces of the latter, an adjustable collar on the push rod, a collar movable on the arbor to open the die, lateral and peripheral cam portions on the collar, a pin movable into engagement with a lateral cam portion to open the die and being movable to an inactive position by a peripheral cam portion, a spring for moving the pin toward the collar, a shoulder on the pin, a longitudinally movable latching member for engagement behind the shoulder to hold the pin retracted, a spring for moving the member to engage behind the shoulder, an abutment on said member, a rod movable by said push rod, an adjustably mounted block on the rod, a wedge member pivoted to the block and having a laterally projecting lip, said wedge member adapted to engage the abutment to withdraw the latching member from the shoulder, means for biasing the wedge member to the abutment-engaging path, and a pivotally mounted lever engaging the pin and adapted to contact with said lip when the pin moves toward the cam collar, whereby the wedge member is disengaged from the latching member abutment and the latter member moves immediately toward the pin and engages behind the shoulder of the latter as soon as such pin is moved to inactive position by a peripheral cam portion.

12. In a threading machine, the combination of a hollow arbor, an opening and closing die carried by the arbor, a work holder, a carriage for the work holder, a collar movable on the arbor for opening and closing the die, peripheral and lateral cam portions on the collar, a pin movable into engagement with a lateral cam portion to open the die and being movable to inactive position by a peripheral cam portion, means for biasing the pin toward the collar, latch mechanism for holding the pin in disengaged position, push rod mechanism extending through the arbor and into the die to an extent determined by the desired length of thread and adapted to be moved by the work, means operated by the push rod to release the latch mechanism, whereupon the pin moves to engage a lateral cam portion to open the die, means operated by upward movement of the pin to disengage the push-rod operated means from the latch mechanism, whereby the pin may be latched in inactive position when it is moved out by a peripheral cam portion, and means operated by backward motion of the carriage to move the collar to close the die.

In testimony whereof I hereunto affix my signature this 27th day of February, 1924.

WILLIAM T. GABLE.
